UNITED STATES PATENT OFFICE.

CHAMPLAIN L. RILEY, OF NORTH PLAINFIELD, NEW JERSEY, ASSIGNOR TO CLARK,
MACMULLEN & RILEY, INC., A CORPORATION OF NEW YORK.

CARRIER APPARATUS.

Application filed March 3, 1922. Serial No. 540,811.

To all whom it may concern:

Be it known that I, CHAMPLAIN L. RILEY, a citizen of the United States, residing in North Plainfield, Somerset County, New Jersey, have invented a new and useful Carrier Apparatus, of which the following, taken in connection with the accompanying drawing, is a specification.

My invention relates to carrier apparatus or machinery, and more particularly to such apparatus used in laundries. The objects of my invention are to increase the output of the laundry or machinery with which my invention is associated or co-operates, to eliminate interruptions and delays in the work of the machinery and its operatives, to reduce manual labor and to expedite and facilitate the handling and transporting of the goods. The manner and means for accomplishing the foregoing and other objects and advantages of my invention will appear more in detail in the following:

The present embodiment of my invention is an apparatus particularly designed to carry the work or goods from the shakers or folders to the feeders of the ironing machines. According to present laundry practice the washed goods, preparatory to ironing, are carefully shaken out, folded if necessary and smoothly and evenly arranged by experienced operatives on boards or rails in such condition and arrangement that the goods may be smoothly and evenly fed to the ironing machines. These latter machines are costly, not only as installations but in operation, since they consume considerable power in exerting the pressure and friction necessary in ironing, and also considerable heat to maintain the ironing temperature. Being of considerable width they also require a crew of a number of feeder operatives, who stand along the width of the machine, to keep them supplied with work to their capacity. Any interruption or delay in the steady supply of work to these machines and their operatives entails therefore, considerable loss.

According to present practice, the boards or rails (which are of a length approximately equal to the width of the ironing machine), having been loaded with goods ready for ironing, are manually carried to position in front of the ironing machine feeders and between them and the machine. This, as will be apparent, requires that the

feeding of the ironing machine must be interrupted, since all the feeders must stop feeding and move away from their machine to allow the empty board or rail to be removed and a loaded board or rail moved into its place. In many cases also the shaker or spreader crew must also similarly cease work to allow of the board or rail they have just loaded being removed from its loading position to its position at the ironer and an empty board or rail moved to position for loading. Furthermore, owing to the length of the boards and their weight when loaded, especially with dampened goods, at least two operators are required to move the boards or rails from one position to the other. My invention is devised to overcome these objections and to permit of a practically continuous operation of the ironing machines and to move the boards or rails from one position to the other without manual labor and without requiring the ironer feeding crew or the spreading and loading crew to move out of their working positions during the substitution of loaded for empty boards or rails or vice versa.

In the accompanying drawing I have illustrated one embodiment of my invention, it being understood that the invention is not limited to the specific form shown.

Figure 1 represents a side elevation of the apparatus.

Figure 2 represents a sectional elevation on a plane transverse to Figure 1.

Figure 3 is a diagrammatic view showing the means for controlling the operation of the apparatus.

In the embodiment of my invention illustrated in the drawing the carrier or delivery device proper comprises a pair of rotary members or wheels, 1, 1, spaced apart one from the other a distance corresponding to the width of the ironing or other machine to which the work is to be delivered. Wheels 1, 1, are mounted in axial alinement, each on a bearing or stub axle 2, 2, respectively, supported in standards or pedestals 3, 3, that are bolted or otherwise secured to the floor 5, of the work room. Between said standards an opening is provided in the floor to form a space or pit 4 to accommodate the lower portions of the wheels and the work carried thereby. Over said opening or space 4, and approximately on a level therewith, a platform 6, is supported in such relation

that it constitutes the working or feeding position for the feeders or similar operators of the ironing or other machine, indicated at 7. Said platform 6 is supported between 5 the wheels or carrier-members 1, 1, by means of struts or hangers 8, 8, suspended on the squared ends of the shafts or axles 2, 2 as shown in Figure 2. This platform is within 10 and clear of the path of movement of the wheels 1, 1, and of the work carried thereby. 10 A guard rail, such as indicated at 9, may be provided to protect the operators from the moving parts.

At intervals around each of the wheels 15 laterally projecting studs or pins 10 are provided on which the work supports 11 are suspended. These work supports consist of longitudinal boards or rails, such as employed in laundries for holding the work 20 prepared for feeding to the ironing machines. In my apparatus such work supports are of a length to extend from one of the wheels or carrier members 1, to the other and thus correspond in length also to the 25 length of the feed-board 12 of the ironing machine. These work-supports 11 have secured to their ends brackets or hangers 13, formed at their upper ends as hooks 14 for taking over or engaging with the studs 10 30 of wheels 1, 1, which thus form pivotal supports at each end of the work-supports. In the apparatus shown, I have arranged these supporting studs 10 at intervals of approximately 60° apart around the rim of wheels 35 1, 1, thus making provision for six work-supports 11 to be carried by the wheels. The arrangement is such that when one of the work-supports 11 is at the feeding position, or feed board 12 of the ironing machine, another work-support on the opposite side of the wheels will be in convenient position for loading or for placing on the studs 10. Also other work-supports that have previously been loaded with work and placed on 40 the wheels are ready to move successively into the feeding position at the ironing machine when the wheels are rotated.

Any convenient means may be provided for rotating the carrier members or wheels 50 1, 1. In the apparatus shown I have provided electric motors 15 for this purpose, one for each wheel, and mounted on platform 6, preferably on the side thereof opposite that occupied by the feeders or ironing machine 55 operators. The weight of the motors in this position tends to counterbalance that of the feeders and thus equalizes or distributes the load on said platform and its supports. The motor pulleys are connected by any suitable 60 form of power transmission, such as belts or chains, to pulleys or sprockets 16, 16, on the hubs of the wheels 1, 1. The motors are of the same size and design and being energized from the same source of current run 65 at the same speed. Other means for driving

the wheels 1, 1, synchronously or in unison may be provided, as, for example, by belting the pulleys or sprockets 16, 16, to a common power shaft. It will be understood that the carrier-members or wheels are rotated intermittently, their rotation being arrested during the time a work-support 11 is at the feed board 12 and its load of work is being fed to the ironing or other machines 7. For this purpose I have provided a combined detent 75 and motor-control mechanism comprising stops 17 arranged at suitable intervals around the rims of the wheels 1. Co-operating with and in the path of said stops is a spring-pressed latch 18, pivotally mounted 80 on a bracket secured to platform 6. Said latch is in the form of a bell-crank its rearward extension 19 forming a foot-lever for operating said latch. Arranged below the foot-lever 19 and in its path of movement is a switch 20 controlling both motors, in the manner hereafter described. It will be understood that the latch 18 and stops 17 are duplicated for each of the wheels 1, 1. The arrangement of the parts described is such 90 that both wheels 1, 1, are held in stationary position by the latches or detents 18 and that the motor switch is open in this position, no power being consumed while the work supports 11 are at the feeding position and 95 being unloaded and the work fed to the ironing machine. When it is desired to rotate the wheels 1, 1, to bring the next loaded work-support 11 to the feeding position, the operator presses the foot-lever 19, thereby 100 releasing latches 18 and in the same movement of the foot-lever closing the motor switch, whereupon the motors are energized and rotate wheels 1, 1, until they are again arrested by the stops 17 next in succession 105 engaging the latches 18, whereupon the foot-lever being released, the motor switch is opened and the current shut off from the motors.

In order to give head clearance to the operators on platform 6 at the work or feed position of the ironing machine, I provide means for swinging the work-supports 11 outwardly and upwardly after they leave the unloading position at the ironing machine. Such means comprise a suitably supported track 21 arranged adjacent each of the wheels 1, 1, and running upwardly and rearwardly from a point adjacent the unloading position of the work-supports to a 115 point at the uppermost portion of the wheels 1, 1, from whence it continues directly rearward on a downward inclination to a loading station. From the loading station the track returns to a point adjacent the wheels 1. The brackets 13 at the ends of the work-supports 11 are provided with rollers 22 that run on the track and are engaged thereby 120 when the said work-supports are at the unloading or feeding position at the ironing 130

machine. As soon as wheels 1, 1, in their rotation carry the unloaded work-support upwardly, rollers 22 on the brackets thereof ride along the track 21. A portion of the 5 track, indicated at 21^a, is deflected outwardly from the axis of the wheels, forming a cam. On entering this portion of the track the rollers 22, riding thereon, swing the work-supports outwardly and upwardly, as shown 10 on the drawing, thus giving full head clearance for the feeders on platform 6. On leaving the cam portion 21^a of the track, the work supports are turned in reversed position so that the further rotation of the 15 wheels 1 move their pivot studs 10 out of the bracket hooks 14, and the work-supports are thereby automatically detached from the wheels and are then supported by the track down the inclined portion of which they roll 20 by gravity to the loading station.

At the loading station a portion of track 21^c is pivoted to the main portion 21 and normally spring-sustained, as by spring 21^d, in full-line position. When an empty work-support reaches this portion of the track it 25 may be held there temporarily if the return portion 21^b of the track is occupied. By depressing the hinged portion 21^c of the track to broken-line position the work-supports 30 run on to the return portion 21^b of the track. From the loading station work supports loaded with work prepared for the ironing machine are returned to the carrier-members or wheels 1, 1, to be carried in 35 turn to the feeding position at said machine. The loaded work-supports run by gravity to the carrier wheels down track 21^b, which is inclined downwardly toward said wheels. Track 21^b thus forms a continuation of track 40 21, so that the work-supports are loaded with prepared work without removing them from the track in their travel from and return to the carrier wheels. At the end of the track 21^b adjacent the wheels, a relatively 45 short section 23 thereof is pivotally jointed to the remainder and may be locked in alignment therewith. Connected to said track section 23, so as to move therewith, is a hand lever 24, provided with a lock release latch 25, so that by pressing said release and operating the lever, as indicated in the drawing, the end section 23 of the track may be dropped from under the work-supports, leaving the latter suspended by 50 their hooks 14 on studs 10 of the wheels 1, and said wheels 1 free to rotate. The end of track section 23 adjacent the carrier wheels is slightly turned up, as at 26 to form a safety stop to prevent overrunning of the 55 work supports. The end of track section 23 is so arranged with respect to the carrier wheels 1, 1, that when said wheels are at rest with a work-support in the feeding or unloading position at the ironing machine 60 and track section 23 is in alined position, the hooks 14 of the brackets 13 of a work-support on said track section 23 will come in registry with the supporting studs 10 on the carrier wheels. By this arrangement a loaded work-support traveling down track 70 section 23 will bring up with its hooks 14 engaged over studs 10 on the carrier-wheels, so that the work-supports are automatically transferred to and re-engaged with the carrier wheels, whereupon track section 23 may 75 be dropped, as described, leaving the work-support suspended on the carrier wheels and the wheels free to rotate to bring the succeeding work support into the unloading or feeding position and simultaneously move 80 the supporting studs 10 into position to receive the next loaded work-support.

In some circumstances, as where the capacity of the laundry, or of the ironing or similar machine used is not sufficiently 85 great, or where the work may be so arranged that the rate of preparing the work for the ironing machine may be kept at about the same pace as the rate of feeding it thereto, it may be unnecessary to remove 90 the work-supports from the carrier wheels. In such cases the work-supports may be loaded while supported on the carrier wheels, the arrangement being such that when a work-support is being unloaded at the feed 95 position of the ironing machine, another empty work-support will be in convenient position on the other side of the wheels for loading, so that unloading and loading may proceed simultaneously without removing 100 the work-supports from the wheels. Where this method of operation is desired those portions of the track that serve to carry the work-supports away from and back to the wheels may be omitted or removed, and only the cam portion 21^a retained for the 105 purpose of deflecting or swinging the work-supports outwardly and upwardly to give head clearance for the workers occupying platform 6.

In the diagram Fig. 3, taken in connection with Fig. 1, I have shown means for automatically starting and stopping the carrier-wheels. The motors 15 are connected in an electrical circuit 31 across 115 the mains M¹, M², which circuit includes the branches x, y, controlled in alternation by a pair of three-way starting and stopping switches, 29, 28. Starting switch 29, is actuated by foot-lever 19, and moved thereby from contact 29^b (where it was left on the preceding actuation of the foot-lever) to contact 29^a, and stopping switch 28 being on contact 28^a (where it was left at the preceding arrest of the carrier-wheel 1), the 120 circuit from M¹, through 31, motor 15, contact 28^a, branch y, contact 29^a, 31, to M² is thus closed and the motors energized, rotating the carrier-wheels. Rotation of the 125 wheels proceeds until one of the trips 27, 130

1 arranged at intervals around the rim of the wheel, strikes one of the switch fingers 28^a of switch 28, thereby moving said switch off contact 28^a on to contact 28^b, thereby opening the motor circuit. It will be understood that the trips 27 are so spaced around the wheel and in such relation to the work-supports thereon as to actuate the stop switch to open the motor circuit at the proper moment for stopping the carrier wheels with a work-support in the feeding position at the ironing machine. To insure that the detent 18 will be released from the stops 17 when the starting switch is actuated, I have connected to said detent a solenoid core, the solenoid 30 of which is in branch circuit 32 leading from M¹ to a point in the circuit 31 such that when the starting switch 29 closes the motor circuit 20 solenoid 30 will be energized by current flowing from main M¹, branch 32, solenoid 30, switch 28 and branch x (or y) to M². The solenoid will thus be energized, and detent 18 released, simultaneously with the 25 closing of the motor circuit by starting switch 29. It will similarly be deenergized and detent 18 returned to locking position simultaneously with the actuation of the stopping switch 28.

30 It will be seen that my invention provides means for moving longitudinal work-supports laterally to a working position as rapidly as the capacity and continuous operation of the working machinery, such as ironers, may require and without necessitating that the feeding crew or operators move away from their working positions. Prior to my invention, so far as I am aware, no means were known or used for accomplishing this result. Furthermore my invention eliminates the manual lifting and carrying of the supports loaded with prepared work and the attendant risk of dropping, soiling, and disarrangement of the same. My invention 40 also enables continuous operation at full capacity of such machines as ironers, in which interrupted or less than full-capacity operation entails considerable loss.

50 Various changes and modifications may be made in the form, construction and arrangement of the various parts and mechanism from those herein particularly shown and described without departing from the broad characteristics and principles of my invention.

55 Claims.

1. Apparatus of the character described comprising an operator's working station, longitudinal work-supports, and a carrier device carrying said work-supports laterally to and away from the working station between the operator and his work in a path that clears the operator at said station.

60 65 2. Apparatus of the character described comprising longitudinal work supports and

a carrier device therefor moving between a loading and an unloading station for said supports, said carrier device moving said supports laterally in a closed loop path that includes within it an operator's work position.

3. Apparatus of the character described comprising the combination with the feeding table of a machine, of a platform for the machine feeder, supports for the work to be fed to the machine, and a carrier device on which said supports are carried, said carrier device carrying said supports laterally around said platform and between the same and said feeding table.

4. Apparatus of the character described comprising the combination with the feeding table of a machine, of a platform for the machine feeder, supports for the work to be fed to said machine, a carrier device on which said supports are carried, said carrier device carrying said supports laterally around said platform and between the same and said feeding table, and means under control of the feeder on said platform for starting the carrier device and stopping the same with a work-support in working position at the feeding table.

5. Apparatus for moving prepared work to the feed position of an ironing machine, said apparatus comprising longitudinal work supports and a carrier for said supports moving between a loading station for said supports and the feed position of the ironing machine, said carrier moving said supports laterally in a path that clears the feed operators at the ironing machine.

6. Apparatus of the character described comprising longitudinal work supports, a carrier device on which said supports are mounted, said carrier moving said supports laterally between a loading and an unloading station in a path that clears an intervening operator's position, and means for arresting the movement of the carrier when the supports are at the loading and unloading stations.

7. Apparatus of the character described comprising longitudinal work supports, an operator's platform, a carrier device on which said supports are mounted, said carrier moving said supports laterally from a loading station in rear of said platform to an unloading station in front of said platform in a path that clears the platform.

8. Apparatus of the character described comprising longitudinal work-supports, a carrier for moving said supports laterally between loading and unloading stations in a path that clears an intervening work position, said work-supports mounted on the carrier at spaced intervals that correspond to the space between the loading and unloading stations whereby one support is at the loading station when another is at the

unloading station, and means for arresting the carrier at said stations.

9. Apparatus for delivering prepared work to the feed position of an ironing machine, said apparatus comprising longitudinal work-supports, a feeder's platform for the ironing machine, and an intermittently moving carrier on which said supports are mounted, said carrier moving said supports laterally downward from their loading station and laterally upward from their feed position and in a path that clears said platform and feeders.

10. Apparatus of the character described comprising a pair of spaced-apart carrier-members, longitudinal work-supports mounted at their ends on said carrier members, said carrier-members moving said supports laterally in a loop path that incloses an operator's work position.

11. Apparatus of the character described comprising a pair of spaced-apart carrier-members moving between a loading and an unloading station in a loop path, work-supports mounted at their ends on said carriers and carried laterally thereby, a work position between said carrier members and inside the path of travel of said supports, and means for intermittently actuating said carrier members.

12. Apparatus of the character described comprising a pair of spaced-apart carrier-members, an operator's platform between said members, longitudinal work-supports having a loading station and an unloading station on opposite sides of said platform, said work-supports mounted at their ends on said carrier-members and moved thereby between said stations in a path clear of said platform and its operators, and means for intermittently actuating said carrier-members in unison.

13. Apparatus of the character described comprising a pair of spaced-apart intermittently rotating carrier-members, longitudinal work-supports mounted at their ends on said members and moved thereby laterally to and away from an operator's work position in a path that clears said work position.

14. Apparatus for delivering prepared work to the feed position of an ironing machine, said apparatus comprising a feeder's platform for said machine, a carrier-member at each end of said platform moving between a work-loading station in rear thereof and the feed position of the ironing machine, and longitudinal work-supports mounted at their ends on said carrier-members and carried thereby between said loading station and feed position in a path that clears said platform and feeders.

15. Apparatus for delivering prepared work to the feed position of an ironing machine, said apparatus comprising a feed-

er's platform for said machine, a pair of rotary carrier-members mounted one at each end of said platform, longitudinal work-supports mounted at their ends on said carrier-members and carried thereby laterally in a path that clears said platform, and means for arresting the rotation of the carrier-members when a work-support comes to the feeding position of the ironing machine.

16. Apparatus of the character described comprising a pair of spaced-apart rotary carrier-members, an operator's work position between said members, longitudinal work-supports mounted at their ends on said members and carried thereby laterally in a curved path about said work position, means for deflecting said work-supports during a portion of their travel, and means for actuating said carrier-members in unison.

17. Apparatus of the character described comprising a pair of spaced-apart rotary carrier-members moving between work-loading and unloading stations, an operator's work position between said carrier-members and loading and unloading stations, said carrier-members moving in a curved path downwardly from the loading station and upwardly from the unloading station, a plurality of longitudinal work-supports mounted at their ends on said carrier members, and means for intermittently rotating said carrier members in unison.

18. Apparatus of the character described comprising a pair of spaced-apart rotary carrier-members, an operator's platform around which said carrier-members travel, longitudinal work supports pivotally mounted at their ends on said members and carried thereby laterally in a path that clears said platform, and means for swinging said supports on their pivots during a portion of their travel to enlarge their path of clearance.

19. Apparatus of the character described, comprising a pair of spaced-apart rotary carrier members, work-supports carried by said carrier-members, an operator's platform around which said work-supports travel, means for automatically detaching unloaded work-supports from the carrier-members, and means for automatically attaching loaded work-supports to said carrier-members to replace the detached unloaded work-supports.

20. Apparatus of the character described comprising a pair of spaced-apart, intermittently rotating carrier-members, longitudinal work-supports mounted at their ends on said members, means for automatically detaching unloaded work-supports from said members, and means for automatically attaching loaded work-supports to said

members in place of the detached work-supports.

21. Apparatus of the character described comprising a pair of wheels spaced apart and mounted to rotate in parallel planes, a plurality of work-supports carried by said wheels, means for manually starting and automatically stopping the rotation of said wheels, means for automatically detaching 10 the work-supports from the wheels at a predetermined point in their path of travel, means for removing the detached work-supports from the wheels, means for returning said work supports to said wheels 15 at another predetermined point in the rotation of the wheels, and means for automatically attaching said work-supports to said wheels on their return thereto.

22. Apparatus of the character described 20 comprising the combination of a carrier, supports for the material to be carried thereby, means on said supports for pivotally engaging and attaching the same to said carrier, a track adjacent the carrier, a portion 25 of said track forming a cam, and rollers on said supports arranged to co-operate with said cam to swing the supports about their pivots to a detaching position.

23. Apparatus of the character described 30 comprising the combination of an operator's platform, a carrier for carrying material to the operator on said platform, supports for the material carried detachably engaged to the carrier, and means automatically operated after a support has been carried past 35 the operator for detaching the same from the carrier.

24. Apparatus of the character described 40 comprising the combination of an operator's platform, a carrier for carrying material to the operator on said platform, means under control of the operator for starting and stopping the carrier, supports for the material carried detachably engaging the carrier, and means automatically operated after a support 45 has been carried past the operator for detaching the same from the carrier.

25. Apparatus of the character described 50 comprising the combination of an operator's platform, a carrier for carrying material to the operator in a path that clears said platform and the operator thereon, supports for the material carried detachably engaging the carrier, and means automatically operated after a support 55 has been carried past the operator for detaching the supports from the carrier.

26. Apparatus of the character described 60 comprising the combination of a carrier, work-supports having hook members detachably engaging the same to the carrier, rollers on said work-supports, a track adjacent the carrier and having a portion thereof in the path of said rollers, said track

portion being cam-shaped to move said 65 work-supports into position for detaching their hook-members, and another portion of said track inclined downwardly away from the carrier whereby the continued movement of the carrier detaches the same from the 70 work-supports leaving the latter supported on their rollers on said track portion and free to travel along the same away from the carrier.

27. Apparatus of the character described 75 comprising a pair of axially aligned and spaced apart carrier-wheels, means for intermittently rotating said wheels in unison, a plurality of work-supports, means on said work-supports for detachably engaging the 80 same with said carrier-wheels, tracks for said supports leading from said wheels to a loading station and from the loading station back to said wheels, means in the path of travel 85 of said supports for detaching them from said wheels and transferring them to said track, and means for transferring said supports from said track and attaching them to the carrier-wheels.

28. Apparatus of the character described 90 comprising a carrier, work-supports having means thereon for detachably engaging said carrier, rollers on said work-supports, means co-operating with the carrier for automatically delivering the work-supports to and 95 detaching the same from the carrier, said means comprising a track adapted to be engaged by the rollers of the work-supports, one portion of said track being cam-shaped and in the path of the rollers of the work-supports carried by the carrier to move said 100 supports to detaching position, another portion of said track inclined away from the carrier, another portion of said track inclined toward the carrier, a flexibly mounted 105 track section between said inclined portions, and manually controlled means on the track portion inclined toward the carrier for transferring the work-supports thereon from said track portion to the carrier.

29. Apparatus of the character described 110 comprising a pair of spaced-apart and axially lined carrier-wheels, a fixed operator's working platform supported between said wheels, means on each of said wheels for engaging 115 and supporting between them work-supports to be carried by said wheels, means for rotating said wheels in unison, and means for simultaneously arresting said carrier wheels when a work-support thereon arrives 120 at the working position of an operator on said working platform.

30. Apparatus of the character described 125 comprising a pair of spaced-apart carrier-wheels, said wheels mounted in axial alignment, means on each of said wheels for engaging and supporting between them work-supports to be carried by said wheels, an

operator's working platform supported between said wheels and within the path of movement of said work-supports carried by the wheels, a loading station for loading said work-supports on to said wheels, said loading station being outside the path of movement of said wheels, means for rotating said

wheels in unison, and means for simultaneously arresting said wheels when a work-support thereon is at the working position of an operator on said platform and with the said supporting means is at the loading station. 10

CHAMPLAIN L. RILEY.
